UNITED STATES PATENT OFFICE.

WILLIAM W. SHONK, OF VANDALIA, ILLINOIS.

SAW-SWAGE.

SPECIFICATION forming part of Letters Patent No. 412,676, dated October 8, 1889.

Application filed April 13, 1889. Serial No. 307,076. (No model.)

To all whom it may concern:

Be it known that I, WILLIAM W. SHONK, a citizen of the United States, and a resident of Vandalia, in the county of Fayette and State 5 of Illinois, have invented certain new and useful Improvements in Band-Saw Swages; and I do declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 Figure 1 of the drawings is a representation of the invention applied to the saw and is a perspective view. Figs. 2, 3, 4, 5, 6, and 7 are detail views.

This invention relates to certain improvements 20 in saw-swages more particularly designed for band-saws; and it consists of the combination of parts and their novel construction, as will more fully appear from the following description.

25 In the embodiment of my invention I employ a suitable support or standard A, let into a socket of the foot a, which in practice is bolted to the floor. This standard or support is offset, as at a', toward and slightly over- 30 hangs a bracket a², cast upon said standard.

B B' are two clamps vertically adjustable upon the standard or support A. The lower one B is swiveled upon a screw-rod b, which is worked or adjusted by a hand-wheel c, resting 35 or bearing upon the bracket a², said screw-rod passing through said bracket. In these clamps are grooves to receive the saw-blade. The upper clamp B' is formed with a slight elliptical hub-like extension d', arranged with- 40

in the plane of the inner sides of a proximate U-shaped slot b² in the extreme upper end of the standard or support A, which will again presently be referred to; also, in the upper clamp B' is the swaging-die C, which is so ar- 45

ranged as to be properly presented to the saw-tooth to be operated upon, and is manipulated by a lever or handle C', carrying the same, and limited in its movement to the left hand by a stop C², projecting from clamp B'. To 50

the lever or handle is also connected a pivoted rod c', carrying the saw-blade feeder c²,

which comprises a socketed arm c³, secured by a set-screw c⁴ upon said rod and adapted to engage the teeth of the saw-blade and thus permit of the movement of the latter as the 55 lever or handle C' is worked, bringing the required tooth up against the swaging-dies. The arm c³ has depending from one end a projection c⁵, and upon it is secured a horizontal plate c, which glides over the points of the saw-blade teeth, assisting the lifting of the arm from one tooth to another, while the projection c⁵ aids in preventing the displacement of the arm or feeder. Stops c⁷ and c⁸ project from the clamp B' to form a rest for rod c' 60 and to limit the movement of the lever C'. The action of the swage or die C is also aided by the opposite diagonally-disposed holding-screw d and clamp-bar d', the latter having its lower end resting upon the back of the 70 tooth at the point, and the screw d bearing upon the clamp-bar d'.

To the opposite side of the implement is applied a cam-lever D, its cam D' also being of approximately elliptical shape, and having in 75 its circumference a spiral groove or channel d², which receives and engages a small projection or stud d³ upon the standard A at one side of the slot b². The journal d⁴ of the cam D' bears in the upper clamp B', said journal 80 passing into an aperture or passage in said cam and in the hub-like extension d' thereof, the inner side of said cam D' bearing against said hub or extension, while its periphery bears against a yoke d⁵ of said standard. This 85 contrivance, when the lever or handle D is turned, not only serves to effect the adjustment of the upper clamp B to the saw-blade, but also serves to clamp the tooth against an opposite set-screw to prevent the distorting 90 or bending of the tooth during the operation of swaging.

Having described this invention, what I claim, and desire to secure by Letters Patent, is—

1. The combination, with the supporting-standard and the saw-blade clamps, of the die-actuating lever or handle carrying the feed device, substantially as specified.
2. The combination, with the supporting-standard and the saw-blade clamps, of the lever or handle actuating the saw-tooth swag-

ing-die and the opposite diagonally-disposed clamp-bar and holding-screws, said bar resting upon the back of the tooth, and the screw bearing upon the clamp-bar, substantially as set forth.

3. The combination, with the supporting-standard and the saw-blade clamps, of the lever or handle actuating the saw-tooth swaging-die, the set or clamp screw bearing against one side of the saw-tooth, and the cam lever or handle whose cam is provided with a spiral groove or channel which receives a projection upon said supporting-standard, the journal of said cam bearing against the tooth in alignment with said clamp-screw, substantially as set forth.

4. The combination of the supporting-standard, the vertically-adjustable saw-clamps, the

lever carrying the tooth-swaging die and the saw-feeding device, the opposite diagonally-disposed clamp-bar and holding-screw, the former bearing upon the back of the saw-tooth at the point and the latter bearing upon said clamp-bar, the clamp-screw bearing against one side of the saw-tooth, and the cam-journals bearing against the opposite side of the tooth, the cam having a spiral groove engaging a projection on the supporting-standard and bearing against a hub-like projection of the upper saw-clamp, substantially as specified.

In testimony whereof I affix my signature in presence of two witnesses.

WILLIAM W. SHONK.
